Samuel T. Parker, Delano & H. & Cham. Brewster & Schuyler, Jr.

Letters Patent

The schedule referred to in these Letters Patent, making part of this patent, containing a description in the name of the late Samuel T. Parker once and breveted themselves of their improvement in the machine for cutting and Chiselling Stone.

To all whom these presents shall come, Be it known that in Samuel T. Parker of the County of Delaware & State of, New York & from Brewster & the County of Schuyler & State aforesaid have invented a new and useful machine for Cutting & Chiselling Stone so that the following is a full and exact description of the construction & operation of said machine as invented by us.

The machine for Cutting or Chiselling Stone as herein claimed by the subscribers consists in the joint place of an upright frame secured into two little bed pieces & consisting of pliant timber.

The upright posts are securely bound by two pieces at top and bottom to the whole firmly secured by Mortise and tenons. At a suitable height from the bottom of the frame two girts are attached to the upright posts & parallel with the bed. Between the girts are placed two horizontal rods, the joint one of which is secured by bolts or otherwise to the girts. While the back rod is made horizontally by means of holes in the sides of the girts. The front rod consists of two pieces parallel and joined together perpendicular to the back. Corresponding notches are made & allow a set of blades. These extend also through the back rod by means of similar notches or apertures. These blades are of an iron or other suitable substance & are furnished mounted the blade with a lip or projection which extends from each side and intersects a corresponding projection on the lower extremity of an upright spring which is attached to the base of the iron, as. The upright spring side outwards has a way to move in easily as occasion requires.

The chisel or iron or other suitable substance & are furnished mounted the blade with a lip or projection which extends from each side and intersects a corresponding projection on the lower extremity of an upright spring which is attached to the base of the iron, as. The upright spring side outwards has a way to move in easily as occasion requires.
